(57) **CLAIM**

The ornamental design for a stand for television receiver, as shown and described.

DESCRIPTION

1. Stand for television receiver

1.1 is a perspective view of a stand for television receiver showing the new design;

1.2 is a front view thereof;

1.3 is a back view thereof;

1.4 is a left side view thereof;

1.5 is a right side view thereof;

1.6 is a top view thereof;

1.7 is a bottom view thereof; and

1.8 is a perspective view showing the stand for television receiver in a state of use.

The broken lines shown in the drawings depict portions of the stand for television receiver that form no part of the claimed design. The broken lines in reproduction 1.8, showing a television receiver and another stand, depict environmental subject matter that forms no part of the claimed design.

1 Claim, 8 Drawing Sheets
